UNITED STATES PATENT OFFICE.

ARTHUR D. RAMSAY, OF LOWELL, MASSACHUSETTS, ASSIGNOR OF ONE-HALF TO
HENRY J. ROGERS, OF LOWELL, MASSACHUSETTS.

BOBBIN-HOLDER FOR ROVING-FRAMES.

1,335,193.

Specification of Letters Patent. Patented Mar. 30, 1920.

Application filed July 2, 1919. Serial No. 308,105.

To all whom it may concern:

Be it known that I, ARTHUR D. RAMSAY, a citizen of the United States, residing at Lowell, in the county of Middlesex and 5 State of Massachusetts, have invented certain new and useful Improvements in Bobbin-Holders for Roving-Frames, of which the following is a specification.

This invention is a device to be attached 10 to what are known as card room roving frames and other similar machines.

The operator of a roving frame receives wooden bobbins upon which roving is wound and places such bobbins on suitable skewers 15 or other devices on what is known as a creel. The roving ends from this creel pass through drawing rollers which are covered with a smooth plate of metal known as a roll cover, thence to the fliers or other devices 20 by which the roving is further twisted and wound on to other smaller bobbins. From time to time, as the bobbins on the creel become empty, the operator goes 25 through the recreeling process, which consists of removing the empty or substantially empty bobbins from the creel and replacing them by full bobbins.

During this recreeling it becomes necessary to do something with the empty bobbins, for if they are thrown upon the floor 30 they are likely to be broken by the operator's feet or by the movement of the trucks, and they are also dangerous as the operator is likely to slip on them. If they are 35 dropped upon the floor they are likely also to become soiled and to pick up floor waste from which they must afterward be cleaned.

As bobbins generally have a head which is larger than the body, they have a tendency 40 to roll in curves and will not stay in place on any smooth surface which has the slightest slope or which is subject to any jar.

It is not feasible to provide baskets or 45 ordinary racks as they would be in the way, and especially would interfere with the operator when doffing, that is, renewing the small filled bobbins on the spindles.

The roll cover is of the most convenient 50 form and in the most convenient position on which to place the empty bobbins, but they will not stay in place on account of the fact that it is smooth and, if it is made rough, with corrugations, pins, spindles, or such like, flyings and other waste will accumulate 55

and it will be difficult to creel, especially without injuring the operator's hands.

It is also desirable to have a device which can be moved out of the way when it becomes necessary to doff the frame or to oil 60 the rollers, and it is desirable to have a device which can be adapted for use with different sizes and makes of machines and of bobbins.

The recreeling takes a relatively small 65 time and I find it desirable to have a device which, except during the recreeling, can be pushed up entirely out of the way so as not to interfere with the operator in any respect.

In the drawings, Figure 1 is a side elevation 70 of part of a roving frame embodying my invention, the roll stand and other parts being broken away to more clearly show the construction. Fig. 2 is a detail substantially 75 a plan view looking from the direction of the arrow in Fig. 1 of part of the roll cover and of our bobbin holder. Figs. 3, 4 and 5 are side elevations showing modifications 80 of our device, and Fig. 6 is a perspective view of another modification. Fig. 7 is a side elevation of a modified form of holding hook.

In the drawings, 10, 11, 12, 13 and 14 85 represent creel bars which support the skewers 8 which carry the various bobbins 20, 21, 22, each of which is filled with roving R. A represents the supporting frame and B represents the drawing rolls, while C represents the roll cover and D represents the fliers which twist and wind the roving R after it passes through the drawing rolls B on to the small bobbins F.

G represents the shipper rod, which is generally in the position shown, on such 95 frames, and 16 represents a guide rod which is a guide for the roving. The above named parts are all old and well known.

My bobbin holder, represented complete 100 by H, includes the front bar 30 in the top of which are a plurality of depressions 31 each adapted to support and hold in place such part of a bobbin as 24, 25, 26, as may rest upon it, and the supporting arms 32, 33, 34, which are shown as fixed at one end 105 thereto. The front bar 30 should be rigid.

Each of these supporting arms, as exemplified by 32 in Fig. 1, comprises a neck 40 which is bent upward and fixed at its end 110 in any suitable manner to the front bar 30, a

shank 41 and a loop 42. This longitudinal loop at the other end is relatively long and of such size that the shipper rod G can pass loosely through it. Each of such loops is 5 preferably open at one point for attachment.

Each arm is turned in at 43 to the shank 41 and is preferably made of more or less elastic metal so that it can be sprung readily over the shipper rod when being put in 10 place. The longitudinal loop is of such length that the whole bobbin holder H can be brought down so that the supporting arms will rest on the roll cover or can be moved back and up and held away from 15 the roll cover by being hooked over a hook, such as 46, fastened to one of the creel bars, such as 10.

It will readily be seen by examining Figs. 1 and 2 that bobbins of various lengths can 20 be placed partly on the bobbin holder and partly on the roll cover, and that they will not roll nor slide out of position, while the bobbin holder can be lifted up out of the way of the operator to permit doffing, oiling, etc. It is also evident that two or more supporting arms can be used.

In Fig. 3, I show a modification of the construction wherein the creel bar hook is dispensed with, the supporting arms each 30 being made with a straight shank 50 which is bent around at 51 to form a longitudinal loop about the shipper rod G, such loop being somewhat longer than shown in Figs. 1 and 2. In addition to this, a suitable 35 weight 52 is attached to the back end of each supporting arm so that, when the bobbin holder is pushed back, the weight will overbalance it and tip it up to the position shown by the dotted lines. This construction 40 cannot be used on most frames but may be used in some cases.

Fig. 4 shows another modification in which the supporting arms comprise a straight shank 60 which extends from the 45 back of the roll cover to the shipper rod G, thence at 61 to form a loop as shown in the other construction. The front bar 62 extends between the supporting arms on a line back of the roll cover so that the bobbins, 50 such as 26, will extend from the back on to the roll cover instead of from the front of the roll cover as in the other constructions. An objection to this type is that, in order to 55 keep the bobbins from slipping endwise, it is desirable that the front bar should be slightly higher than the roll cover, and that the head end of a bobbin should rest on and beyond this front bar. To accomplish this in the construction shown in Fig. 4, it is necessary 60 to turn the bobbin around with the end in a position which is unnatural for the operator.

In Fig. 5, I show a construction in which the front bar 70 is carried by slides, such as 65 71, which are adapted to slide in and out in

suitable grooves or passages 72 in a supporting arm, such as 73, which are shown as pivoted on to any suitable part of the frame, such as 74, by means of straps 75. Set screws, such as 76, permit these slides, and 70 therefore these front bars, to be adjusted and held in position.

It will be understood that while I find the shipper rod a very convenient part of the machine on which to hang my bobbin holder, 75 such bobbin holder can be attached to any other part of the frame, such as 74, provided the supporting arms rest on the roll cover in such manner as to bring the front bar in a position to coöperate therewith preferably 80 so that the depressions therein will be slightly higher than such cover.

Fig. 6 shows a bobbin holder made of one continuous rod of metal, the front bar 80 being so bent as to form depressions 81 and 85 side bars 82 and 83, being bent back upon themselves so as to form longitudinal loops 84 and 85.

In Fig. 7, I show a metal creel bar 90 and a creel bar hook 91 clamped thereto by 90 means of two nuts 93 and 94 screwed upon the threaded shank 95 whereby such hook can be raised or lowered, put in place or removed at will.

I claim:

1. The combination with a roving frame having a roll cover, of a bobbin holder having a plurality of depressions each adapted to support and hold in place part of a bobbin while the other part of the bobbin rests 100 on the roll cover, and so hung from the frame that it can rest on or can be moved and held away from the roll cover at will.

2. The combination with a roving frame having a roll cover, of a bobbin holder which 105 comprises a front bar having a plurality of depressions each adapted to support and hold in place part of a bobbin while the other part of the bobbin rests on the roll cover, and supporting arms for said front 110 bar so formed and attached to the frame that they can rest on the roll cover or that they can be moved away and held away therefrom.

3. The combination in a roving frame 115 having a roll cover, of a bobbin holder which comprises a front bar having a plurality of depressions each adapted to support and hold in place part of a bobbin and supporting arms fixed at one end to said front bar 120 and bent at the other end to form a longitudinal loop.

4. The combination with a roving frame having a roll cover, of a bobbin holder which comprises a front bar having a plurality of 125 depressions each adapted to support and hold in place part of a bobbin while the other part of the bobbin rests on the roll cover, and supporting arms for said front bar so formed and attached to the frame that 130

they can rest on the roll cover or that they can be moved away and held away therefrom, together with means for holding such bobbin holder away from the roll cover.

- 5 5. A bobbin holder for roving frames comprising a relatively rigid front bar having a plurality of depressions each adapted to receive part of a bobbin, and two or more side bars made of elastic metal each fixed at 10 one end to the front bar and each bent around and back on itself at the other end to form an open longitudinal loop.
- 10 6. The combination with a roving frame

having a roll cover, of a bobbin holder which comprises a front bar adapted to support and hold in place part of a bobbin while the other part of the bobbin rests on the roll cover, and supporting arms for said front bar so formed and attached to the frame that they can rest on the roll cover or that they 15 can be moved away and held away therefrom.

In testimony whereof I have affixed my signature.

ARTHUR D. RAMSAY.
